UNITED STATES PATENT OFFICE.

JOHN F. PETERS, OF EDGEWOOD PARK, PENNSYLVANIA, ASSIGNOR TO WESTINGHOUSE ELECTRIC AND MANUFACTURING COMPANY, A CORPORATION OF PENNSYLVANIA.

PARALLEL-FLOW REACTANCE-COIL.

1,295,921.

Specification of Letters Patent. Patented Mar. 4, 1919.

Application filed September 10, 1914. Serial No. 861,041.

To all whom it may concern:

Be it known that I, JOHN F. PETERS, a citizen of the United States, and a resident of Edgewood Park, in the county of Allegheny and State of Pennsylvania, have invented a new and useful Improvement in Parallel-Flow Reactance-Coils, of which the following is a specification.

My invention relates to current-limiting reactance devices and more particularly to improvements in current-limiting reactance coils which are inserted in power circuits as protective means for the electrical apparatus associated therewith.

My invention has special reference to current-limiting reactance coils that are adapted for use in large-capacity power circuits which are traversed by currents of high value.

In power systems, it is of the utmost importance that the service to be rendered be uninterrupted, and that the power-generating apparatus be protected against all short circuits, disturbances, etc., in order to insure reliability of operation. With the development of high-power generating stations and the large-capacity units embodied therein, it is particularly desirable to protect the electrical apparatus from severe strains caused by short circuits and to limit the possible local concentrations of power at such occurrences.

It is highly desirable that the internal losses of power-limiting reactance coils be minimized in order to insure efficient operation of the associated electrical system. To this end, I propose a reactance coil comprising a plurality of spaced copper strands which are connected in multiple to furnish adequate cross sectional area to conduct the load currents. In order to further reduce the internal losses, the several copper strands are so transposed with respect to each other as to reduce the induced currents or internal circulating currents therein. By spacing the copper strands from one another, the heat-radiating capacity of the coil is greatly increased, thereby permitting each strand to be worked at a considerably higher current density than is usually deemed advisable.

Because of the large diameter of, and the difficulty involved in winding a single coil comprising an unduly large number of parallel copper strands, I utilize a plurality of coil sections, each of which comprises a lim-

ited number of copper strands. These coil sections are so positioned with respect to one another as to minimize the floor area required for the installation of the complete reactance coil. Again, the difficulty of winding a coil section is considerably less than that of winding a coil comprising an unduly large number of parallel copper strands, thereby insuring a substantial decrease in the cost of labor. Moreover, the impedance offered to short-circuit currents by my present reactance coil is considerable, by reason of the disposition of the several sections in mutual inductive relationship. In this manner, the magnetic flux, which is responsible for the impedance offered to short-circuit currents by its related sections, is utilized to induce impedance voltages in the other sections mutually inductively related thereto.

In order to understand my invention more clearly, reference may be had to the following description and the accompanying drawings in which Figure 1 is a view, mainly in elevation, but partially in section, of a reactance coil constructed in accordance with my invention; Fig. 2 is a plan view of the coil shown in Fig. 1; Fig. 3 is a diagrammatic representation of my reactance coil; Fig. 4 is an enlarged view, showing the method of interconnecting the coil sections embodied in the coil shown in Fig. 1, and Fig. 5 is an enlarged detail view, partially in section, showing the manner in which a plurality of copper strands, such as are used in building and winding my reactance coil, may be connected.

Referring to Figs. 1 and 2, a plurality of coil sections 1 and 2, each comprising a group of flat spirals 3, are superposed upon each other, substantially as shown in Fig. 1. Radially extending cleats 4, provided with recesses 5 formed on one face thereof, receive copper strands or conductors 6. The cleats 4 brace the coil against internal mechanical stresses that are set up when heavy short-circuit currents flow through the coil and they also space the various convolutions or turns of the spirals from one another, thereby greatly increasing the heat-radiating capacity of the coil. Longitudinally extending tie bolts 7, projecting through openings in the extremities of the cleats 4, hold the coil layers in fixed relation to one another and brace the spirals against external mutual stresses. Insulated supports 8,

comprising porcelain insulators 9 and metallic feet 10 associated therewith, prevent the coil from grounding on the bed plate or floor upon which it may be disposed. Conducting rods 11 and 12, disposed in the opening of the coil and extending parallel to its axis, serve as terminals for the coil. By means of members 13 and 14, which are mounted on the conducting rod 11, it is possible to make electrical connections with the coil at either the top or the bottom. The conducting rods 11 and 12 engage spreaders, shown as Y shaped spreaders 15, which are disposed at the top and the bottom of the coil and brace it against any mechanical forces to which it may be subjected.

Inasmuch as it is desirable that the power-limiting reactance coil offer a minimum reactance to the normal load current and considerable reactance to short-circuit or abnormally large currents, it is usual to provide a non-magnetizable core for the coil. An air core or a core of a non-magnetizable material which will impart a straight-line characteristic to the coil is usually preferred.

Under certain conditions, it may be more economical to supply an iron core for a reactance coil of high impedance. However, I prefer to use air cores, when possible, and have shown my structure so provided. The air core greatly assists in ventilating the coil and in rapidly dissipating the generated heat, in addition to substantially decreasing the total weight of the coil.

As above mentioned, my reactance coil is designed to be utilized in circuits over which large currents flow. Under such conditions, a reasonable number of parallel copper strands would not suffice to carry the load currents unless each strand was of a cumbersome and undesirable diameter. To avoid such condition, I utilize a plurality of coil sections which are connected in multiple, each section comprising a reasonable number of parallel copper strands. In this way, the coil may be cheaply and easily wound.

In order to lend clearness to the drawings and to illustrate my invention in a simple manner, I have shown each coil section 1 and 2 as composed of three parallel copper strands 16, 17 and 18, but it will be understood that, in practice, a larger number of copper strands, as, for instance, seven, eight, nine or more, will usually be employed. Of course the number of the parallel copper strands does not affect the novelty of my invention.

I prefer that the coils be wound by the method disclosed in U. S. Patent No. 1,241,549, issued to Westinghouse Electric & Manufacturing Company, Oct. 2, 1917, on an application filed by myself. That is conductor 16, extending from the binding post 11, engages the inner-

most recess formed in the radial bar or insulator 4. Continuing in the corresponding recess in the next two bars 4, the conductor 16 is then stepped radially outward to the second recess formed in one of the bars 4, while the conductor 17 initially engages the innermost recess of the same bar 4. The conductors 16 and 17 engage the corresponding recess in the next two bars 4 but, on reaching the third bar 4, the conductor 16 engages the third recess thereof and the conductor 17 engages the second recess, while the conductor 18 engages the innermost recess. The three conductors 16, 17 and 18 continue to engage the corresponding recesses in the next two bars 4, but, on arriving at the initial bar 4, the conductor 18 is stepped outwardly to the second recess, the conductor 17 to the third recess, and the conductor 12 to the fourth recess, the innermost or first recess having been previously engaged by the conductor 16 at the beginning of the operation.

As the winding operation is continued and the first layer is nearing completion, the conductor 16, after it engages the outermost recess in the bar 4, is stepped downwardly to engage the corresponding recess in the second layer or series of bars 4, which layer is immediately adjacent to the top layer. Similarly, the conductors 17 and 18 successively occupy the outermost notches in the proper radial bar 4 of the second layer and, all of the conductors are wound to progress inwardly toward the center of the coil. When this coil layer is completed, the conductors are stepped to a third layer in which they are wound similarly to the first layer. In employing this method of winding, the copper strands comprising the coil sections are so wound that they all have substantially the same length and impedance in order to entirely eliminate internal circulating currents. The efficiency of the coil is thus greatly increased, by reason of the substantial elimination of internal losses.

Referring to Fig. 3, the relationship between the coil sections 1 and 2 and the direction of the current flow therethrough are illustrated. Leads 19 and 20, each of which represents the three copper strands 16, 17 and 18, are connected together to constitute the terminal 11. Leads 21 and 22, representing the same copper strands, are connected together to constitute the terminal 12 by the clamping means to be described in connection with Figs. 4 and 5.

In building up the coil, the lower section 2 is first wound by operating the winding machine or lathe in one direction. The lead 20 of Fig. 3 constitutes the starting lead and the lead 22 constitutes the finish lead when winding the coil section 2. A conductor comprising this coil section may be traced in a counter-clockwise direction from the 18

terminal 20 to the terminal 22. Likewise, the current is directed through this coil section in a counter-clockwise direction, as indicated by the arrows. After the section 2 is completely wound, the upper section 1 is wound by operating the winding machine in the reverse direction. The lead 21 constitutes the starting lead and the lead 19 the finish lead when winding the coil section 1. A conductor comprising this coil section may be traced in a clockwise direction from the terminal 21 to the terminal 19. The current, however, is directed through this coil section in a counter-clockwise direction, as indicated by the arrows. The finish leads 22^a of the lower section 2 and start leads 21^a of the upper section 1, being adjacently disposed midway between the ends of the reactance coil, are then connected together to constitute the terminal 12. As a result, the two coil sections do not need to be insulated from each other, as would be the case if said sections were wound in the same direction and the start leads or finish leads of both sections were connected together. Start or lower leads 20^a of the lower section 2 are connected to finish or upper leads 19^a of the upper section 1 to constitute the terminal 11.

The arrows in Fig. 3 indicate that the current flows in both coil sections in such a direction that they are positively and mutually inductively related, and, inasmuch as the sections are so wound as to have equal impedances, equal quantities of current will flow through them. As a result, the magnetic fluxes induced in the coil sections are additive and will flow in the same direction through them. Therefore, the impedance of each coil section results from its own induction and the induction imparted by the other section. Consequently, the total impedance offered by the coil will be greater than the impedance offered by two separate coils so disposed as not to be positively and mutually inductively related to each other.

While I have shown and described a reactance coil comprising two superposed sections which are connected in parallel relationship and so constituted as to take equal quantities of load current, it will be understood that any number of coil sections may be utilized which will insure adequate cross sectional area of the copper strands for conducting normal currents.

In Figs. 4 and 5, I have illustrated a device by means of which the conductors constituting the terminal 12 may be connected together. For the purpose of illustration, I have shown fourteen parallel conductors which represent the copper strands employed building up one of the reactance coils. The seven copper strands constituting the upper coil section, in connection with the seven copper strands constituting

the lower coil section, embrace the central rod 23 upon which they are circumferentially disposed, as shown in Fig. 5. The rod 23 embraced by the copper strands constitutes the portion of the terminal 12 which is disposed within the coil opening. All of the copper strands meet at adjacent points 23^a of the coil which in this particular instance, are disposed midway between the ends of the coil, as shown in Fig. 1. Clamps 24, which embrace the fourteen conductors and the central rod 23, are spaced from one another and along the rod 23 to hold the copper strands securely in fixed relationship to one another. Each clamp 24 comprises two segments 25 and 26, each of which is provided with an extending portion 27 and lugs 28 which admit of insertion of bolts 29. It will be seen that the segments 25 and 26 are electrically insulated from each other by an insulating washer 30 which embraces a tie bolt 29^a. This structure prevents the formation of eddy currents and consequently, keeps the internal losses within the coil down to a very small value.

While I have herein shown and described a preferred embodiment of my invention, it will be understood by those skilled in the art, that various modifications may be made without departing from the spirit and scope of my invention, and I desire that only such limitations shall be imposed as are indicated in the appended claims.

I claim as my invention:

1. A current-limiting reactance coil comprising a plurality of superposed coil sections which are positively and mutually inductively related and oppositely wound, each section being composed of a plurality of flat parallel spirals and the corresponding leads of the sections being connected in multiple to constitute terminals for the coil.

2. A current-limiting reactance coil comprising two superposed coil sections which are mutually inductively related, each section being composed of a plurality of parallel conductors wound to form a series of flat parallel spirals, the lower leads of the lower section being connected to the upper leads of the upper section and the upper leads of the lower section being connected to the lower leads of the upper section to constitute coil terminals.

3. A current-limiting reactance coil comprising two superposed and parallel-connected coil sections which are positively and mutually inductively related and reversely wound, each coil section being composed of conductors wound to form a series of spirals.

4. A current-limiting reactance coil comprising two superposed coil sections which are connected in multiple and are positively and mutually inductively related and reversely wound, each coil section being com-

posed of a plurality of parallel-connected and spaced conductors wound to form a series of flat parallel spirals.

5. A current-limiting reactance coil comprising two superposed coil sections which are mutually and inductively related and reversely wound, both coil sections being composed of conductors wound to form a series of flat parallel spirals, one terminal of the coil comprising the leads of sections which terminate midway between the coil ends, and the other terminal of the coil comprising leads of the sections which terminate at the coil ends.
- 10 6. A current-limiting reactance coil comprising two superposed coil sections which are positively and mutually inductively related, both coil sections being composed of conductors wound to form a series of flat parallel spirals, one terminal of the coil comprising the leads of the sections which terminate midway between the coil ends and the other terminal of the coil comprising leads of the sections which terminates at the coil ends.
- 15 7. A current-limiting device comprising a plurality of coil-sections positioned in mutual inductive relationship, each of said coil-sections comprising a conductor wound in the form of a built-up column of superposed spirals, the terminals of said coil-sections being interconnected with one another so as to connect said coil-sections in parallel relationship whereby the total inductance of
- 20 8. A current-limiting device comprising a plurality of inductive coil-sections which are mutually inductively related and reversely wound, and means whereby the simultaneous current flow through said separate sections produces co-existing alternating-current fluxes in the same direction to increase the inductance of each separate
- 25 9. A current-limiting device comprising

two inductive coil-sections severally formed of a built-up column of superposed spirals, said coil-sections being mutually inductively related and reversely wound, and means for connecting said coil-sections in parallel relationship and for so directing the currents flowing therethrough that the total inductance of said device exceeds the inductance of the separate coil-sections.

10. A current-limiting reactance coil comprising a plurality of separate coil-sections, and a connecting device for directing the current flow through said separate sections, said device comprising a central rod, a plurality of electric conductors circumferentially and longitudinally disposed thereupon, segments provided with lugs and extending portions embracing the conductors, bolts co-operatively engaging the lugs to hold said segments in fixed relationship, and an insulating sleeve embracing one of said bolts to insulate the segments from each other.

11. A current-limiting reactance coil comprising a plurality of separate coil-sections, and a connecting device for directing the current flow through said separate sections, said device comprising a central rod, a plurality of electric conductors circumferentially and longitudinally disposed thereupon, and clamps embracing the conductors, each clamp comprising segments each of which has one lug disposed at one end and a second lug disposed a short distance from the other end to provide an extension, bolts co-operatively engaging the lugs to hold the segments in fixed relationship, and an insulating sleeve embracing one of said bolts to insulate the segments from each other.

In testimony whereof, I have hereunto subscribed my name this 25th day of Aug., 1914.

JOHN F. PETERS.
